ELECTRODE GUN SUCH AS IS USED IN
CATHODE-RAY TUBESHilary Moss, London, England, assignor to A. C.
Cossor Limited, London, England, a British
companyApplication January 26, 1948, Serial No. 4,368
In Great Britain March 14, 1942Section 1, Public Law 690, August 8, 1946
Patent expires March 14, 1962

8 Claims. (Cl. 250—155)

1

This invention relates to electron guns such as are used in cathode ray tubes for the purpose of generating electron beams, and of focussing them at least mainly by electrostatic fields.

One of the objects of the invention is to produce an exceptionally fine crossover in the electron beam.

In an electron gun according to the invention, the first anode and the control electrode, which serve with the cathode to establish the first electron lens, each consist of an apertured disc electrode having a cup portion surrounding the aperture, formed by dishing and disposed convex towards the cathode, and said anode and control electrode are so arranged that the aperture of the anode is situated within the cup portion of the control electrode.

An object of a preferred form of the invention is to focus the electron beam into a fine spot on a target such as a fluorescent screen. This may be effected by employing a single or unipotential lens to produce on the target an image of the crossover. Preferably the potential of the first and last electrodes of this lens is equal to that of the first anode and thereby the introduction of a third lens between the first lens and the unipotential lens is avoided. A direct connection may be made between said electrodes and the first anode, either inside the tube or in an external circuit.

The appended drawing shows in Fig. 1 a cross-sectional view of an electron gun structure in a cathode ray tube embodying principles of the present invention, while Fig. 2 shows diagrammatically a cathode ray tube embodying a modified form of the invention.

Cathode 1 is of a conventional type having a flat active surface disposed perpendicular to the axis 00 of the gun. Control electrode 2 comprises a cup portion 21 convex towards the cathode 1. This cup is formed by dishing. In the middle of the bottom of the cup is an aperture 22.

The first anode 3 has a cup portion 31 convex towards the cathode, also formed by dishing. In the middle of the bottom of this cup is an aperture 32. This aperture 32 lies within the cup portion 21 of control electrode 2.

In a specific example of a gun according to the invention, which has been found to operate satisfactorily, the cups 21 and 31 of the electrodes 2 and 3 are both of part-spherical form and have equal radii of 3.17 mm. The diameter of the aperture 22 in the control electrode is 0.8 mm. and that of the aperture 32 in the first

anode is 1.8 mm. The depth of the cup in the control electrode is 2.07 mm. and that of the cup in the first anode is 1.87 mm.

The spacing between the aperture of the control electrode and the cathode surface is 0.3 mm. The spacing between aperture of the first anode and that of the control electrode is 1.50 mm.

The crossover is formed within the cup of the control electrode and near the aperture of the first anode.

The beam diverges from the crossover as it passes into a tubular second anode 4. A single lens is formed by the electrostatic field between second anode 4, final anode 5 and the decelerating electrode 6; anodes 4 and 5 being maintained at equal potential, the highest potential in the gun and preferably equal to that of the first anode 3, while electrode 6 is maintained at a lower potential. The arrangement of potentials is indicated generally in Fig. 2 by the sign and number of the polarity marks adjacent the various leads.

The electron beam leaves the electron gun through aperture 51 of final anode 5 and the beam is now in a form convergent towards a fine spot.

It has been found convenient and effective to work this tube with the following electrode voltages relative to cathode:

Control electrode 2	2 to 50 volts negative
First anode 3	2,000 volts positive
Second anode 4	
Final anode 5	
Decelerating electrode 6	270 volts positive

An image of the crossover is then produced at a distance from final anode 5 about seven times the distance of that anode from the first anode 3.

The electron gun which is shown in cross-section in Fig. 1 of the drawing may be modified as shown in Fig. 2 by the introduction of an additional apertured disc electrode 41 located between anodes 3 and 4 and directly connected to the latter this electrode having an aperture 42 of diameter 1.8 mm. The divergent beam is masked down by this additional electrode so that electrons do not impinge on the decelerating electrode 6. Undesirable secondary emission from electrode 6 is thus avoided.

In Fig. 2 I have indicated the electron gun structure as being mounted within neck portion 60 of cathode ray tube envelope 61.

I claim:

1. A cathode ray tube having an electron gun

2

10 The spacing between the aperture of the control electrode and the cathode surface is 0.3 mm. The spacing between aperture of the first anode and that of the control electrode is 1.50 mm.

15 The crossover is formed within the cup of the control electrode and near the aperture of the first anode.

20 The beam diverges from the crossover as it passes into a tubular second anode 4. A single lens is formed by the electrostatic field between second anode 4, final anode 5 and the decelerating electrode 6; anodes 4 and 5 being maintained at equal potential, the highest potential in the gun and preferably equal to that of the first anode 3, while electrode 6 is maintained at a lower potential. The arrangement of potentials is indicated generally in Fig. 2 by the sign and number of the polarity marks adjacent the various leads.

25 The electron beam leaves the electron gun through aperture 51 of final anode 5 and the beam is now in a form convergent towards a fine spot.

30 It has been found convenient and effective to work this tube with the following electrode voltages relative to cathode:

Control electrode 2	2 to 50 volts negative
First anode 3	2,000 volts positive
Second anode 4	
Final anode 5	
Decelerating electrode 6	270 volts positive

35 An image of the crossover is then produced at a distance from final anode 5 about seven times the distance of that anode from the first anode 3.

40 The electron gun which is shown in cross-section in Fig. 1 of the drawing may be modified as shown in Fig. 2 by the introduction of an additional apertured disc electrode 41 located between anodes 3 and 4 and directly connected to the latter this electrode having an aperture 42 of diameter 1.8 mm. The divergent beam is masked down by this additional electrode so that electrons do not impinge on the decelerating electrode 6. Undesirable secondary emission from electrode 6 is thus avoided.

45 In Fig. 2 I have indicated the electron gun structure as being mounted within neck portion 60 of cathode ray tube envelope 61.

I claim:

50 1. A cathode ray tube having an electron gun

aperture thereof and disposed with its convex side adjacent said cathode, and an apertured disc first anode having a cup portion surrounding the aperture therein and disposed with its convex portion within the cup portion of said control electrode, and means forming a unipotential lens for converging said stream to a fine spot including in succession a tubular second anode, an apertured decelerating electrode and an apertured final anode, said decelerating electrode and final anode being cup-shaped and having their cupped sides adjacent one another, and means for preventing said stream from impinging on the intermediate electrode of said lens, including an apertured disc electrode following said first anode and having a potential applied thereto equal to that of said tubular anode.
